CLAIM

The ornamental design for an automated chemistry analyzer for analysis of blood components or other body fluids, as shown and described.

DESCRIPTION

FIG. 1 is a perspective view of an automated chemistry analyzer for analysis of blood components or other body fluids, showing my new design.

FIG. 2 is a front view of the analyzer;

FIG. 3 is a top plan view of the analyzer;

FIG. 4 is a left side view of the analyzer;

FIG. 5 is a right side view of the analyzer;

FIG. 6 is a bottom plan view of the analyzer;

FIG. 7 is a rear view of the analyzer.
